UNITED STATES PATENT OFFICE.

CLEARMONT V. BEST, OF CANTON, OHIO.

VAPOR-BURNER.

SPECIFICATION forming part of Letters Patent No. 812,247, dated February 17, 1885.

Application filed December 7, 1883. (No model.)

To all whom it may concern:

Be it known that I, CLEARMONT V. BEST, a citizen of the United States, residing at Canton, in the county of Stark and State of Ohio, 5 have invented certain new and useful Improvements in Vapor-Burners, of which the following is a specification, reference being had therein to the accompanying drawings.

This invention relates to improvements in 10 vapor-burners, it pertaining more especially to burners of the class shown and described in my previous Patent No. 283,956, dated August 28, 1883. The burner forming the subject-matter of said patent had a vertically-ar- 15 ranged mixing-chamber, a horizontal supply-duct, an angular heating-plate, B, and an in- clined passage communicating with the mix- ing-chamber near the upper end, the angular heating-plate extending upward and inward 20 from the mixing-chamber and then downward toward the supply-duct.

Under some circumstances I have found that 25 burners of another character are necessary, which I produce by combining with the mix- ing-chamber and the supply-duct a curved shield or heating-plate and horizontally-ar- ranged webs or flanges adapted to retain the heat which tends to be thrown laterally away 30 from the retort portion of the burner.

30 Figure 1 is a side elevation of a burner embodying my improvements. Fig. 2 is a longitudinal vertical section through the plane of the duct which carries the vapor to the mixing-chamber. Fig. 3 is a longitudinal vertical section on the plane of the duct which carries the vapor from the mixing-chamber to the heating-jet orifice. Fig. 4 is a side view of a modified form. Figs. 5 and 6 are longitudinal vertical sections of that in Fig. 4. Fig. 35 7 is a side elevation of a burner having a hood or guard applied to its lower end to prevent the entrance of insects into the mixing-chamber. Fig. 8 shows a modified form of guard. Fig. 9 is a top view of the burner shown in Fig. 4, and Fig. 10 is a top view of the burner shown in Fig. 1.

In the drawings, A represents the supply 40 pipe or duct, which may be of any suitable character and connected with a reservoir of any preferred style. The supply-duct is filled or packed with corundum, which I have found to be much superior to those materials heretofore in use for this purpose. Cotton, emery,

and other substances have been employed for this packing; but I have found one or another 55 of various disadvantages incident to each, those avoiding one disadvantage having others inci- dent to it. The corundum which I employ I have found to be more durable and less liable to clog the passage-way than are those with 60 which I am acquainted that have been hereto- fore employed. The burner which is secured to the supply-duct A consists of a threaded tubular part or socket, B, a duct, C, extending downward from the part B to cross duct 65 E, a valve-seat, F, and a mixing-chamber, G, these parts being all preferably cast integrally together, the passage-ways for the ducts C and E being formed by drilling after the metal has been cast into the desired shape. It will be 70 seen that the feed-pipe or supply-duct termi- nates at a point in close proximity to the wall of the mixing-chamber G; that the parts above described as forming the burner are all com- 75 pactly arranged, and that the mixing-cham- ber has the main portion thereof situated be- low the central horizontal line of the feed- duct or supply-pipe. Therefore I can not only readily bring to bear a portion of the vapor in the mixing-chamber for the purpose of 80 heating—that is to say, can not only readily withdraw it after it has been mixed with a sufficient amount of air to induce good com- bustion—but can provide a retort portion which can be kept very hot, it consisting of the above- 85 described ducts passing through the metal por- tion referred to, and these being all compactly arranged, the heat can not only be retained, but can be brought to bear at the point where it is necessary to vaporize the oil. 90

H represents the inclined duct which con- 95 veys a portion of the vapor out from the mix- ing-chamber to the orifice h, where the heat- ing-jet is burning. In the construction shown in Figs. 1, 2, and 3 this jet plays upwardly and somewhat inwardly, and in order to prevent the escape of the heat I combine with the parts above described a heating-plate, I. In the construction shown in last-described figures this is made by casting a plate at the 100 inner end of the socket portion B, situated substantially as is shown in the full and dotted lines in Fig. 2, and afterward bending down the outer end of the plate until the end lies in the angle between the socket portion 105 and the mixing-chamber G. This plate oper-

ates to throw downwardly and backwardly the heated currents, and also by conduction absorbs a great part of the heat and carries it downward to the retort portion. The hot currents which are thrown downward I prevent from escaping before they have imparted their heat to the retort portion, and this I accomplish by means of two laterally-extending webs or flanges, J, J, brazed to or cast with the socket portion B. When these webs or wings are used, I utilize nearly all the heat which is generated by the heating-flame to assist in vaporizing.

Below the socket portion B there is a supplemental heating web or flange, K, preferably triangular in face view, and integral or in contact with both the socket portion and the vapor-duct C, it operating to conduct from the socket portion B a large amount of heat down along said duct C, keeping the latter at a high heat.

Much trouble and inconvenience are incident to vapor-burners as heretofore constructed, from the fact that the insects which are attracted by the light frequently enter the open space between the needle-valve and the mixing-chamber and clog it, this often going so far as to nearly extinguish the lights. I have succeeded in obviating this trouble by combining with the burner a hood or guard, which, while allowing the free entrance of the air which is necessary to prepare the vapor for combustion, at the same time prevents the entrance of insects. This hood or guard is represented at L. It may be made of pieces of wire-gauze shaped to fit tightly around the said open space, or it may be made of sheet metal perforated.

I prefer to cast the burner with a laterally-expanded plate, as shown at M, at or near the upper end of the needle-valve, which plate serves to support the lower part of the hood or guard, the upper being attached to or resting against the mixing-chamber wall.

In Figs. 4, 5, and 6 I have shown a modified form of the burner, it embodying, however, the features constituting the essential part of the present invention. In this case the heating-plate I extends downwardly from the socket portion B, and is curved inwardly at the lower end, which rests against or is secured to the vapor-duct C. The heating-vapor duct H extends downwardly on an inclined line through the knot of metal between the tube A and chamber G to the space between the heating-plate I and the vapor-duct. The heat which is generated by the heating-flame is partly absorbed by the heating-plate I, and by conduction carried to the adjacent portions of metal and partly carried upward by the currents of air warmed thereby. The latter part of the heat, however, is prevented from being wasted in this construction also by the use of the laterally-extended wings or webs J, which intercept the hot currents and withdraw the heat therefrom, and by conduction carry it to the retort portion of the burner.

What I claim is—

1. In a vapor-burner, the combination, with the supply-tube A, the mixing-chamber G, 70 the socket portion B, consisting of a knot of metal cast integral with the mixing-chamber, and the vapor-duct C, formed in the said metal and situated in proximity to the mixing-chamber, of the web I, connected with the socket-piece B at its inner end, and curved outwardly to a point inside of and in proximity to the mixing-chamber, and the inclined heating-duct H, formed in said knot of metal said duct being formed independently of the shield I, and having its outer end within the space surrounded by said shield and arranged to throw the jet backward or inward toward the supply-duct A, substantially as set forth. 80

2. The combination of the mixing-chamber a socket portion, B, at the inner or upper end of the mixing-chamber, and having a knot of metal between the end of pipe A and the mixing-chamber, a vapor-duct, C, running directly down by the side of the mixing-chamber and communicating with the socket in the portion B, the heating-vapor duct communicating with the mixing-chamber near its upper end and situated in said knot of metal 90 by the side of the duct C, the heating-plate I, formed independently of the heating-vapor duct and bent or curved to surround the outer end thereof, and the shield J, substantially as and for the purposes set forth. 95

3. A vapor-burner adapted to be secured to a supply-pipe A, having the socket portion B, the mixing-chamber G, the vapor-duct C by the side of the mixing-chamber, inclined duct H, for the heating-vapor, having its inner 105 orifice at or near the upper end of the mixing-chamber and its outer orifice behind the mixing-chamber and in close proximity to the inner end of the supply-tube A, the shields J, J, behind the mixing-chamber integral with 110 the socket portion B, and situated in a horizontal plane between the upper and lower portions of said socket portion, and the shield I, curved or bent, substantially as set forth, around the outer orifice of the heating-vapor 115 duct, as described.

4. The combination, with the vapor-burner having the mixing-chamber G, provided at the lower end with an enlarged opening for the admission of air, the valve and valve-support F below said aperture, the shield M, carried by said valve-support, and the perforated or reticulated insect-guard secured at its lower edge to said plate M, and at its upper edge secured to the mixing-chamber above the air-opening, substantially as set forth. 120

In testimony whereof I affix my signature in presence of two witnesses.

CLEARMONT V. BEST.
